(57) **CLAIM**

The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

The broken line immediately adjacent to the shaded area in the heel element represents an unclaimed boundary of the design. The broken lines showing of a circular eyelet, a shoe lace, and the remainder of the shoe represent unclaimed subject matter and form no part of the claimed design.
